UNITED STATES PATENT OFFICE.

HOWARD CRAMER, OF JACKSONVILLE, FLORIDA, ASSIGNOR OF ONE-HALF TO
LAWRENCE RICHARDSON, OF LOUISVILLE, KENTUCKY.

HUB LINER FOR RAILWAY LOCOMOTIVE WHEELS.

1,426,715.

Specification of Letters Patent. Patented Aug. 22, 1922.

Application filed August 11, 1920. Serial No. 402,927.

To all whom it may concern:

Be it known that I, HOWARD CRAMER, citizen of the United States of America, residing at Jacksonville, in the county of 5 Duval and State of Florida, have invented certain new and useful Improvements in Hub Liners for Railway Locomotive Wheels, of which the following is a specification.

The invention relates to improvements in 10 hub liners for railway locomotive wheels.

It is an object of the invention to provide a liner that may be applied to a locomotive or other railway wheel to prevent lateral play of the wheel relative to a journal box.

15 The invention more particularly has in mind the provision of a liner that may be applied to the inside of the wheel from the outer side thereof, without in any way removing the wheel, or portions of the journal box.

20 The invention broadly comprehends a wear plate that is welded to the vehicle hub so that the same is rigidly supported in position, and is not subject to displacement by vibration of the vehicle.

25 It is a further object of the invention to provide a liner which is inexpensive in construction, and may be attached to the vehicle hub without dropping the same from the locomotive or car.

30 In the accompanying drawings I have disclosed the preferred embodiments of the invention, but this disclosure is merely made for the purpose of illustration, and it is apparent that the liner may be materially

35 changed without departing from the spirit of the invention.

In the drawings, Figure 1 is a side elevation of a locomotive driving wheel with a two part liner applied thereto.

40 Figure 2 is a section on the lines X—X of Figure 1.

Figure 3 is a perspective view of one section of the liner; and,

45 Figure 4 is a perspective view of a modified form of the device.

Referring now more particularly to the drawings, wherein like reference characters indicate corresponding parts, the numeral 1 represents a locomotive driving wheel 50 having the usual spokes 2, and hub 3, mounted upon an axle 4.

55 In the use of locomotive wheels it has been found necessary to provide a means to take up the lateral play between the side of the journal box and the wheel hub which is

caused by a wearing away of the contacting surfaces of these parts, and the present invention contemplates the provision of a removable liner adapted to be secured to the vehicle hub to compensate for this wear. 60 The liners may of course be of the desired material and thickness depending upon the extent of the lateral play existing between the hub and journal box. In the accompanying drawings the numerals 5 and 6 designate sections of the liner shown in Figure 1, said liner being of a metallic formation and of the appropriate thickness. Each section has projecting therefrom integral straps

65 7 extending around the hub of the wheel between adjacent spokes and these straps are united to the wheel by welding. The body of the liner may also be united to the wheel hub by welding, but this is not essential as a welding of the straps will maintain 70 the sections in position very rigidly so that they will not be disturbed by the vibration of the locomotive.

75 It will be observed that the liner is preferably composed of two sections, the ends 80 of each section being beveled as indicated by the reference character 8, which beveled ends may be autogenously welded and thereby maintain the two sections as an integral unit. The straps 7 passing around the hub 85 of the wheel are of course also autogenously welded so that the entire liner is very firmly united to the vehicle hub.

85 In Figure 4 of the drawings I have disclosed a modified form of the invention, 90 wherein the liner is composed of a single piece or yoke section of a somewhat elongated formation having the lugs 9 that are adapted to pass between vehicle spokes and are welded to the hub. With this construction as well as the construction shown in the other figures of the drawings, it will be apparent that the liner is welded to the vehicle hub from the exterior thereof, and it is therefore not necessary to drop the wheels 95 from the locomotive or car when a wear plate is to be applied. The same may be united to the wheel without in any way dismantling the locomotive, and it will also be appreciated that by welding the wear plate 100 in the manner indicated, no fastening screws or the like are necessary.

105 In the prior art, liners have been used that are attached to the wheels by mechanical fastenings, but vibrations and stresses are so 110

severe that these fastening devices will not hold the liners in place with sufficient rigidity. They tend to loosen or crystallize, thereby releasing the liner, which then drops from between the hub and its journal box. By means of the autogenous weld a fastening of ample strength is provided, such fastening being inherently rigid and therefore cannot be accidentally displaced by vibration and stresses.

While in the accompanying drawings, I have described the liner as being attached to a vehicle hub, it will of course be understood that the same may be satisfactorily secured to the journal box without departing from the invention. It will also be understood that I have merely described several preferred embodiments of the invention, and that the liner is subject to many changes without departing from the spirit of the invention.

Having thus described the invention, what I claim is:—

1. A liner of the character described adapted to be interposed between a railway journal box and a wheel, said liner having a body and extensions projecting between the spokes of the wheel accessible from the outside thereof, said extensions being welded to the railway wheel.

2. A liner of the character described adapted to be interposed between a railway journal box and a wheel, said liner having a body and extensions projecting between the spokes of the wheel accessible from the outside thereof, said extensions being secured to the railway wheel to maintain the liner in position.

3. A metallic liner of the character described adapted to be interposed between a railway wheel and a journal box to take up lateral play therebetween, said liner having

an extension projecting from the body thereof to a point around the hub between a pair of adjacent wheel spokes to be secured to the railway wheel.

4. A metallic liner of the character described adapted to be interposed between a railway wheel and a journal box to take up lateral play therebetween, said liner having an extension projecting from the body thereof to a point around the hub between a pair of adjacent wheel spokes to be secured to the railway wheel by welding to maintain the liner in position.

5. A metallic liner of the character described adapted to be interposed between a railway wheel and a journal box to take up lateral play therebetween, said liner having an extension projecting from the body thereof to a point around the hub between a pair of adjacent wheel spokes to be secured to the railway wheel by welding to maintain the liner in position, said liner consisting of connected sections united to each other by welding.

6. A liner of the character described adapted to be interposed between a railway journal box, and a wheel, said liner having a body and an extension projecting from said body to a point between certain spokes of the wheel to be accessible from the outside of the wheel and to be united to the wheel by welding.

7. A liner of the character described having a metal body portion adapted to be interposed between a journal box and a wheel, said liner having a projecting relatively narrow portion projecting beyond the body and between adjacent spokes of a wheel, and by which the liner is fixedly secured to the wheel.

In testimony whereof I affix my signature.
HOWARD CRAMER.
